UNITED STATES PATENT OFFICE.

FRANK S. CROWELL, OF TOLEDO, OHIO, ASSIGNOR TO THE EDWARD N. RIDDLE CO., OF TOLEDO, OHIO, A CORPORATION OF OHIO.

DESIGN FOR A PORTABLE LAMP.

60,895.

Specification for Design.

Patented Apr. 25, 1922.

Application filed January 22, 1921. Serial No. 439,306. Term of patent 7 years.

To all whom it may concern:

Be it known that I, FRANK S. CROWELL, a citizen of the United States, and resident of Toledo, in the county of Lucas and State of Ohio, have invented a certain new and ornamental Design for a Portable Lamp, of which the following is a specification, reference being had to the accompanying drawing, forming part hereof.

Fig. 1 is a perspective view of a portable lamp, embodying my new design.

Fig. 2 is a cross sectional view of one-half section of the base.

I claim:

The ornamental design for a portable lamp, as shown.

FRANK S. CROWELL.
